UNITED STATES PATENT OFFICE.

CHARLES W. HUNT, OF WEST NEW BRIGHTON, NEW YORK.

DRIVING MECHANISM FOR CARS ON INCLINED RAILWAYS.

SPECIFICATION forming part of Letters Patent No. 443,768, dated December 30, 1890.

Application filed October 31, 1890. Serial No. 369,945. (No model.)

To all whom it may concern:

Be it known that I, CHARLES W. HUNT, a citizen of the United States, residing at West New Brighton, in the county of Richmond and State of New York, have invented an Improvement in Driving Mechanism for Cars on Inclined Railways, of which the following is a specification.

In many railways the track for the cars is often level, or nearly so, for a considerable distance, and then such track is inclined for the cars to reach a higher level, and a rack and gear-wheel have been used in propelling the cars up the incline to prevent the slipping of the wheels. In cases where an electric or similar motor is used it is advantageous to have the motor-shaft longitudinal and central, or nearly so, and to connect the same by gearing to the cross-shaft and place the driving-gear and the rack at one side of the central line.

In the drawings, Figure 1 is a cross-section representing the truck-wheels and frame and the driving-gear and stationary rack. Fig. 2 is a longitudinal section showing the positions of the respective parts; and Fig. 3 is an end view, partially in section, with two driving-gears.

The car-wheels A A', axles B B', and truck-frame C are of any usual or desired character, and the cross-shaft D is at a higher elevation than the axles B B', but parallel to the same, and this cross-shaft is supported in suitable bearings upon the truck-frame and driven in any desired manner. I have represented a longitudinal shaft E, connected by the bevel-pinion G and bevel-wheel G' with the cross-shaft D, and this cross-shaft D is shown as sufficiently high above the axles B B' to allow the driving-shaft E to pass freely over the axle B', and there may be cranks or any suitable gearing for connecting the cross-shaft D with the axles B B', so as to rotate the wheels A A' by such connections only when the car is on a level or nearly-level track; but upon the cross-shaft D there is a gear-wheel R, the pitch-line of which corresponds to the diameter of the car-wheels at the tread of the same, and in consequence of the cross-shaft D being higher than the axles B B' the stationary rack

S can be between the rails T T and at a higher elevation than such rails. Hence the gear-wheel R is out of the way when the car is propelled by the wheels A A', as usual, and such gear-wheel does not become injured and the teeth full of dirt, and when the car reaches the base of an incline the teeth on the wheel R gear into the teeth on the rack S, and the power is exerted both upon the wheels A A' and the gear R to propel such car up the incline without the risk of the wheels slipping upon the track.

It is generally preferable to make use of driving-gears at the central portion of the truck for connecting the motor with the cross-shaft D. Hence the gear-wheel R and rack S are at one side of the center line. To accommodate this condition it is usually preferable to employ a second wheel R' upon the shaft D at the same distance from the vertical center of the truck as the wheel R, so that when the motor is traveling the other end first upon the track the wheel R' will gear with the rack S.

In some instances the inclines upon the track are steeper at some places than at other places, and more power is required for drawing the train upon the steeper incline. In consequence of providing two gear-wheels R and R', Fig. 3, a second rack S may be made use of upon the incline, and the necessary strength of gearing will thereby be obtained by the second rack and gear-wheel, instead of using throughout the road heavier gear-wheels and racks.

In consequence of the teeth upon the rack S being higher than the top of the rails T, switches and turn-outs can be provided, because the gear-wheel R is sufficiently high to pass above said switches and turn-outs, and in such cases it sometimes is necessary to notch the rack S at the places where the switch or turn-out rails pass across the same.

I claim as my invention—

1. The combination, with the car-wheels and axles, the driving-shaft passing across one of the axles, a cross-shaft parallel to the axles and at a higher elevation, bevel-gearing for connecting the cross-shaft and the driving-shaft, a gear-wheel upon the cross-shaft, and

a stationary rack upon the track at the inclined portion thereof, substantially as set forth.

2. The combination, with a cross-shaft and
5 two gear-wheels upon such cross-shaft, of a
rack between the track and nearer to one rail
than the other and coinciding with one of the
gears, so that one of such gear-wheels will
mesh with the rack when the locomotive is
10 either end first on the track, substantially as
specified.

3. The combination, with the car-wheels and

axles, of a driving-shaft passing across one
of the axles, a cross-shaft parallel to the axles,
gear-wheels connecting the driving and cross 15
shafts, a gear-wheel upon the cross-shaft, and
a rack upon the inclined portion of the track,
substantially as specified.

Signed by me this 28th day of October, 1890.

CHAS. W. HUNT.
